UNITED STATES PATENT OFFICE.

CHARLES D. P. GIBSON, OF JERSEY CITY, NEW JERSEY.

PISTON-VALVE FOR ENGINES.

SPECIFICATION forming part of Letters Patent No. 655,929, dated August 14, 1900.

Application filed August 28, 1899. Serial No. 728,766. (No model.)

To all whom it may concern:

Be it known that I, CHARLES D. P. GIBSON, a citizen of the United States, residing at Jersey City, in the county of Hudson and State of New Jersey, have invented new and useful Improvements in Engines, of which the following is a specification.

This invention relates to piston-valves for fluid-pressure engines, and embraces a construction of simple character, particularly adapting valves of the reciprocating class for use with the motive fluids under high pressure.

In the accompanying drawings, Figure 1 is a longitudinal sectional view of so much of an engine as is necessary to illustrate my invention. Fig. 2 is a transverse section taken in the plane indicated by line 2 2 of Fig. 1.

Referring by letter to the said drawings, A is a piston-cylinder, B a piston therein, and C a valve-chest which is connected by ports a with the piston-cylinder adjacent to the opposite ends thereof and is provided at an intermediate point of its length with an opening b for the admission of carbonic-acid gas, steam, or other fluid-pressure. The said chest C contains two bushings D, and its opposite ends are connected by a conduit E with an exhaust F. The bushings are of a less diameter than the chest, so as to afford annular spaces c between them and said chest, and they have heads d at their inner ends and also have two sets of ports e f for connecting their interiors with the said annular spaces, which are always in communication with the ports a. The said ports e e at the inner ends of the bushings D are the induction-ports and are in communication with the central steam-chest C, and the ports f f at the outer ends of the bushings are the eduction-ports of greater area than the ports e e and are in communication with the exhaust-pipe F.

In the chest is a reciprocating rod G and two piston-valves H, fixed thereon, the said valves being so arranged, as shown in Fig. 1, that when one is in a position to effect communication between the interior of the chest C and the cylinder A at one side of the piston B, so as to admit fluid-pressure to said cylinder, the other effects communication between the piston-cylinder at the opposite side of the piston and the exhaust-conduit E, and

thereby exhausts fluid-pressure from the cylinder.

In practice when the valve-rod is moved toward the right the right-hand valve H uncovers the inner port e of its bushing and permits fluid-pressure to pass from the interior of the chest through the port e, the right-hand annular space c, and the right-hand port a into the cylinder and drive the piston toward the left. The left-hand valve H moves with the right-hand one, and as the latter uncovers the port e of its bushing the former uncovers the port f of its bushing and permits the fluid-pressure at the left of the piston to pass out through left-hand port a, left-hand annular space c, left-hand port f, and conduit E. When the valve-rod is moved toward the left, the operation described is repeated, with the exception that the left-hand valve H effects communication between the interior of the chest and the interior of the cylinder, while the right-hand valve effects communication between that portion of the cylinder at the right of the piston and the exhaust-conduit E.

From the foregoing construction and arrangement of the parts it will be seen that the use of packing-boxes in the steam-chest containing the high-pressure motive fluid is entirely avoided, the only sliding bearing for the valve-rod G being in the exhaust-pipe, and this may be simply a guide or a packing-box, so loosely packed that but little frictional resistance is offered to the movement of the valve-rod, and it will also be observed that the valves H H are perfectly balanced.

Having thus described my invention, what I claim is—

The combination with the cylinder and piston of a fluid-pressure engine, of a steam-chest having ports or openings at its ends communicating with the ends of the cylinder, and a central chamber to which the motive fluid under pressure is supplied, valve-seat bushings fitted in the ends of the steam-chest formed to leave an annular space around them into which the cylinder-ports open, and each having a series of induction-ports at its end adjacent to the central fluid-receiving chamber and a series of eduction-ports at its outer end, pipe connections at the ends of the steam-chest to place the eduction-ports in

communication with a common exhaust-pipe, a valve fitted to slide in each of the bushings, and an operating-rod connecting the valves and passing through a bearing or packing box
5 formed or located in one of the pipes connecting the ends of the steam-chest to the exhaust-pipe.

In testimony whereof I have hereunto set my hand in presence of two subscribing witnesses.

CHARLES D. P. GIBSON.
